UNITED STATES PATENT OFFICE

117,822

DESIGN FOR A COMBINED TIE CLASP AND COMB

Tony L. Pogue, Mays Lick, Ky.

Application August 29, 1939, Serial No. 86,935

Term of patent 7 years

To all whom it may concern:

Be it known that I, Tony L. Pogue, a citizen of the United States of America, residing at Mays Lick, in the county of Mason and State of Kentucky, have invented a new, original, and ornamental Design for a Combined Tie Clasp and Comb, of which the following is a specification, reference being had to the accompanying drawing, forming a part thereof.

I claim:

The ornamental design for a combined tie clasp and comb, as shown.

TONY L. POGUE.
